To all whom it may concern:

Be it known that I, ARTHUR KNAUER, a citizen of the German Republic, residing at West Reading, in the county of Berks and State of Pennsylvania, have invented a new, original, and ornamental Design for an Elastic Fabric, of which the following is a specification, reference being had to the accompanying drawing, forming part thereof.

Fig. 1 is a face view of the elastic fabric.

Fig. 3 is a view similar to Fig. 1 but showing the reverse side of the fabric.

In the views the fabric is shown enlarged approximately 1½ times actual size, but which in the reduction to patent size will show the fabric approximately actual size.

I claim.

In testimony whereof I affix my signature.
